CARBURETOR

Jay S. Culp, Detroit, Mich., assignor to William F. Connolly, Detroit, Mich.

Application July 13, 1931, Serial No. 550,553

9 Claims. (Cl. 261—50)

The invention relates to carburetors of that type in which the fuel is supplied to the jet by a mechanical pump which operates only when the engine is running. It is the object of the invention to obtain a construction which will permit of rapid acceleration and to also effectively idle, and will automatically adjust for operation under different conditions of load and speed. It is a further object to obtain a simple construction of mechanism and to secure various other advantages as hereinafter set forth.

In the drawings:

Figure 1 is a vertical central section through my improved carburetor;

15 Figure 2 is a cross section in the plane transverse to that of Figure 1 and showing a different position of adjustment;

Figures 3 and 4 are horizontal sections respectively on lines 3—3 and 4—4 of Figure 1.

20 As shown, A is the engine inlet manifold which is provided with an upwardly extending inlet portion B to which the carburetor casing is attached. This carburetor casing includes a central member C which is secured to the portion B by suitable means such as the screws D. The passage through the member C is contracted in its upper portion to be of substantially Venturi form and in the lower portion there is secured a spider member E which supports a centrally arranged 25 upwardly projecting hollow post member F. Slidingly mounted on and guided by the member F is a valve member G which is both manually and automatically operated as hereinafter described. The valve G has a centrally depending 30 stem H which slidably engages the hollow post F. The stem H is hollow and internally threaded to receive the threaded upper end I of a stem member J forming a downward extension of the stem H. At the lower end of the stem J is a collar K which has a lost motion connection with the stem by means of a cross pin L engaging a slightly 35 enlarged aperture L' in the stem. The collar K is also provided with a shoulder for engaging a spring M sleeved upon said collar and having its upper end abutting against a bearing on the post F. Thus the resilient pressure of the spring M tends to draw the stems J and H downward and to withdraw the valve G from engagement with the restricted portion of the air passage through 40 the member C. There is, however, a second spring N which is within the hollow valve G and engages an annular recess in the post member F. The spring N opposes the operation of the spring M but is of lighter tension so that when both are 45 free to operate, the spring M will overcome the spring N and will lower the stem and valve G until the tension of said springs is in balance. However, to the extent of the lost motion between the pin L and the enlarged aperture L' the spring N can operate independently of the spring M to 50 raise the valve G.

Surrounding the casing member C is a bell shaped casing member L provided with radial guide portions O' which telescopically engage the outer cylindrical surface of the member C. The 55 housing O in connection with the casing C forms a return bent air inlet to the manifold. The fuel is introduced through a nozzle P which centrally depends from the bell shaped housing O. This nozzle receives fuel from a conduit Q which in 60 turn receives it from any suitable pump (not shown) operating only when the engine is moving. The discharge of fuel from the nozzle P is metered by a tapered metering pin R which projects upward from the valve G and is provided 65 with a head R' inside the valve and held in position by the stem I. The arrangement is such that the metering pin is permitted sufficient lateral movement to find its seat in the nozzle, and in the normal position of parts when the 70 engine is not in operation the valve G will be held by the spring N so as to completely close the nozzle P by the metering pin R. The housing O is adjustably secured to the housing member C by a bolt S and a spring S' sleeved thereon so that 75 by adjusting this bolt the housing O may be either raised or lowered. This will permit of properly setting the same so as to close the nozzle P by the metering pin R when the engine is not in 80 operation.

As has been stated, the tension of the spring M being greater than the tension of the spring N, it will overcome the latter and lower the valve G and metering pin R. Normally such movement is prevented by a rod T preferably extending 85 upward through a guide T' formed in the manifold A and bearing against the lower end of the collar K. The rod T is operated by a bell crank lever U which in turn is actuated by a rod V leading to the accelerator pedal (not shown).

Operation

When the engine is at rest the nozzle P will be closed by the metering pin R, thereby preventing the discharge of any fuel. As soon, however, as the engine is cranked and suction is produced in the manifold A, this will draw down the valve G against the tension of the spring N to take up the lost motion between the pin L and enlarged recess L'. The amount of 110

movement is only sufficient to draw down the metering pin R so as to open the nozzle for the discharge of fuel required for idling. If, however, the rod V is pushed by the accelerator pedal 5 the bell crank lever U will be rocked, withdrawing its bearing from the lower end of the rod T and permitting the spring N to move downward the collar K, stem J, valve G and metering pin R. This will proportionately increase both the volume 10 of air which can pass through the Venturi passage and also the amount of fuel discharged through the orifice in the nozzle P. The amount of movement under the actuation of the spring M is limited to a point where the diminished tension of said spring is counterbalanced by the increased tension of the spring N. Any further opening movement of the valve is effected 15 through manifold suction. Thus the valve G performs the combined functions of a throttle valve and an automatic air valve, thereby simplifying the construction of the carburetor as a whole. Furthermore, the construction is one which permits rapid acceleration, for the initial opening of the valve G and the metering pin R is accomplished by the excess tension of the spring M over that of the spring N, while for 20 higher engine speeds manifold suction may be depended upon for opening the valve to the extent permitted by the accelerator.

30 What I claim as my invention is:

35 1. A carburetor comprising an air inlet having a downwardly directed portion of Venturi form, a fuel inlet nozzle discharging downwardly in said portion, an air valve in said inlet opening in a downward direction and normally engaging the restricted portion of the venturi, means for holding said valve in its raised position to restrict the passage of air through said inlet, manually operable means controlling said holding means to permit a variable opening of 40 said valve, and metering means controlling the discharge of fuel from said nozzle carried by said valve and adapted to increase the discharge orifice of said nozzle in proportion to the increased opening of the valve.

45 2. A carburetor comprising an air inlet having a downwardly directed portion of Venturi form, a fuel nozzle discharging downwardly in said portion of the inlet, an air valve normally engaging the restricted portion of said venturi to restrict the passage of air therethrough, said valve being movable downwardly to open said passage, manually controlled means for raising said valve, a metering pin carried by said valve and cooperating with said nozzle to increase the discharge orifice in proportion to the opening of 50 said valve, and resiliently yieldable means for raising said valve and metering pin to completely close the orifice in said nozzle, said means permitting the opening of said nozzle to idling position upon initial suction on said valve and limiting means for the movement of said valve which is independent of the manually controlled means.

60 3. A carburetor comprising an air inlet having a restricted portion, a fuel nozzle discharging downwardly in said restricted portion, an air valve engaging said restricted portion to restrict the flow of air therethrough, resilient means for moving said air valve downward to enlarge the air passage, manually controlled means for opposing the downward movement of said valve and for holding the same in various positions, means carried by said valve for metering the discharge of fuel from said nozzle to proportion 65 the same to the air opening, said metering means

being adapted to completely close said nozzle in the highest position of the valve, and yieldable means independent of said manually controlled means permitting a limited movement of said valve to open said nozzle for idling upon initial air suction upon said valve.

80 4. A carburetor comprising an air inlet conduit having a contracted portion, a fuel nozzle arranged axially of said inlet to discharge in said contracted portion, an air valve movable axially of said inlet towards or from said contracted portion, a metering pin carried by said air valve co-operating with said nozzle to variably restrict the discharge of fuel therefrom, means for normally holding said valve in a position to restrict the air passage through said contracted portion of the inlet and to completely close said nozzle by said metering pin, manually operable means for removing said holding means, thereby permitting moving said valve to enlarge the air passage and to correspondingly increase the discharge orifice in said nozzle, and yieldable means independent of said manually operable means permitting a slight movement of said valve and metering pin by air suction to supply the carbureted mixture for idling.

85 5. A carburetor comprising a downwardly directed air inlet conduit having a contracted portion, a bell shaped housing surrounding said air inlet conduit and forming in connection therewith a return bent inlet passage, a fuel discharge nozzle depending from said bell shaped casing and projecting into the contracted portion of said air inlet, a valve movable axially within said air inlet towards or from the contracted portion thereof, a metering pin carried by said valve and cooperating with said nozzle to variably restrict the discharge orifice thereof, manually operable means for moving said valve and means for adjusting said bell shaped housing upon said air inlet to vary the position of said nozzle in relation to said metering pin.

90 6. A carburetor comprising a downwardly directed air inlet having a contracted portion near its upper end, a bell shaped housing surrounding said air inlet conduit and forming in connection therewith a return bent air inlet passage, a fuel nozzle depending from said bell shaped housing to discharge fuel downwardly into the contracted portion of said air inlet, a valve movable axially of said air inlet towards or from said contracted portion, a metering pin carried by said valve and cooperating with said nozzle to variably restrict the discharge orifice thereof, a stem depending from said valve, a bearing with which said stem is slidably engaged, a spring sleeved on said stem and abutting against said bearing, a collar on said stem having a limited lost motion connection therewith, said collar engaging said spring whereby said valve is resiliently actuated in a downward direction, a spring of lighter tension abutting against said bearing and said valve to yieldably lift the latter to the extent of the lost motion between said collar and stem, a member engaging said collar to normally support said valve in a position adjacent to the contracted portion of said inlet and with said metering pin completely closing the discharge orifice in said nozzle, manually operable means for withdrawing said member to permit said first mentioned

95 spring to move said valve and metering pin downward, said second mentioned spring together with the lost motion connection of said collar permitting a slight movement of said valve and metering pin independent of said manually operable means.

erable means to furnish the air and fuel for idling.

7. The combination with an engine manifold provided with an upwardly extending portion forming a downwardly directed air inlet, of a carburetor comprising a casing connected to said upwardly extending portion of the manifold and having a contracted Venturi portion, a bell shaped housing surrounding said casing and forming in connection therewith a return bent air inlet passage to said manifold, a fuel nozzle depending from said bell shaped housing to discharge into the contracted portion of said casing, an air valve movable axially in said casing towards or from the contracted portion thereof, a metering pin carried by said valve and cooperating with said nozzle to variably restrict the discharge orifice thereof, a stem for said valve, a bearing in said casing in which said stem is slidible, a rod extending upward through said manifold to engage said stem and to hold the same in a position where said valve restricts the air passage through said casing and said metering pin closes said nozzle, manually operable means for lowering said rod to permit the opening of said valve and the enlargement of the discharge orifice in said nozzle and resiliently yieldable means independent of said manually operable means permitting a slight movement of said valve under air suction to open said nozzle to supply fuel for idling.

8. A carburetor comprising an air inlet conduit having a contracted portion, a fuel nozzle ar-

ranged axially of said inlet to discharge into said contracted portion, an air valve movable axially of said inlet towards or from said contracted portion, a metering pin carried by said air valve cooperating with said nozzle to variably restrict the discharge of fuel therefrom, opposed springs reacting upon said valve to move the same in opposite directions, said springs being out of balance when said valve is in the restricted portion of said conduit with a preponderance of pressure by the spring urging the valve away from said restricted portion and manually operable means for moving said valve towards said restricted portion adjustable to various positions to limit the opposite movement of said valve.

9. A carburetor comprising an air inlet conduit having a contracted portion, a fuel nozzle arranged to discharge into said contracted portion, an annular valve movable axially of said inlet towards or from said contracted portion, a metering pin carried by said valve cooperating with said nozzle to variably restrict the discharge of fuel therefrom, a guide bearing for said valve, springs abutting against said guide bearing reacting upon said valve to urge the same in opposite directions, said springs being out of balance when said valve is in engagement with the restricted portion of said conduit with a preponderance of pressure by the spring for urging it away from such position, and a manually adjustable stop for variably limiting the movement of said valve away from said contracted portion.
